UNITED STATES PATENT OFFICE.

HERBERT PEARCE AND JOHN ERNEST BILLINGTON, OF BROADBARTH, ENGLAND,
ASSIGNORS TO LINOTYPE AND MACHINERY LIMITED, OF LONDON, ENGLAND.

TYPOGRAPHICAL CASTING-MACHINE.

1,220,782.

Specification of Letters Patent. Patented Mar. 27, 1917.

Application filed September 19, 1914. Serial No. 862,446.

To all whom it may concern:

Be it known that we, HERBERT PEARCE and JOHN ERNEST BILLINGTON, subjects of the King of the United Kingdom of Great Britain and Ireland, both of Linotype and Machinery Works, Broadbath, in the county of Chester, England, engineers, have invented new and useful Improvements in Typographical Casting-Machines, of which

10 the following is a specification.

The present invention consists of improved means for adjusting one or all of the molds of a typographical line-casting machine as well as one of the knives there- 15 of which trim the sides of a line cast therein, all such adjustments being in respect of the ascender side of a line and independent of each other.

It is especially applicable to machines of 20 the Mergenthaler type described in the specification of Letters Patent 436532, 16th September, 1890, and known commercially under the trade mark "Linotype." For that reason, and also because the application of 25 it to such a machine embodies and exemplifies every feature of the invention, such application has been chosen for specification.

The accompanying drawings illustrate a preferred constructional form of that application. In them—

Figure 1 is a front elevation of a mold wheel equipped with four molds, to each of which the invention has been applied:

Fig. 2, a section on the line 2—2 of Fig. 35 1, showing the application of the invention to the ascender knife; and

Fig. 3, a sectional detail.

Referring first to the known parts of the machine included in these figures, 1, 1 are 40 the slots or molds proper in the respective mold blocks 2 fixed upon the front face of the vertical mold wheel or carrier 3 turning upon a fixed axle 4. A slot 1 extends through its block 2 from front to rear, and 45 has cast in it the body of the line, the printing edge of the latter being cast in a mold provided by the respective composed line of matrices (not shown) and with which the slot 1 registers and the front face of the 50 block 2 makes metal tight contact during the act of casting that line. A block 2 consists of a body portion 9, a cap plate 10 held away from it at the desired body dimension of the slot 1, by a liner 25 at each 55 end, and a rearward projection 26 partly on

the portion 9 and partly on the cap plate 10, extending into a cavity 13 in the wheel 3, the four separate pieces 9, 10, 25, 25, being held together by screws 27. It is held to the wheel 3 by the countersunk screws 11, 60 the shanks of which are passed through corresponding round holes in the flange 15 of the body portion 9 and screwed into the wheel. It occupies the respective segment of the wheel 3, its length parallel with a 65 respective diameter of the latter, and all the slots 1 are at a common radial distance from the wheel axis.

Only one mold is in use at a time, and the one to be used is at the top of the wheel 3 70 during the act of casting. A line is cast upside down, *i. e.*, with the tops of its characters on the ascender side 8 of the slot 1 toward the axis of the wheel. Each of the other slots 1 has its ascender side toward 75 the said axis to correspond. After a line has been cast the wheel 3 is turned through three-quarters of a circle in the reverse direction to that taken by the hands of a watch and stopped. Its line is then vertical and 80 opposite the cutting edges of two trimming knives 5, 6. These are vertical and parallel and stationary relatively to the wheel 3, being carried by the so-called vise frame 24. The distance 7 between these knives corresponds with the desired body dimension of 85 the line. The latter is pushed, printing edge first, between the knives 5, 6, by a so-called ejector (not shown), each knife trimming off the respective side of the line any ex- 90 crescence or excess of metal which there may be. The amount of trimming required by 95 and done to the non-ascender (right-hand side, looking at Fig. 2) side of a line, is small, but that required by the opposite or so-called ascender side, is of great importance. It is that side which has a fin cast on 100 it where a slot 1 registers with the respective mold for the printing edge. Further, the amount of trimming done to the ascender side of each line cast in all the slots 1 on the wheel 3, must be the same. In other words, a fin must be trimmed off in the desired plane of the ascender side of its line.

Now it is obvious that if a slot 1 is set too 105 far from the wheel axis the line ejected from it will be only slightly trimmed by the ascender knife 5, the consequence being that the line will be thrown off its foot by the act of locking up the form of which it is part. 110

If, on the other hand, the said slot is too near the axis, the knife 5 will cut too deeply into the ejected line, the consequence being that the capitals and ascenders will lose their heads.

Hitherto a slot 1 has been rigidly set on its wheel 3 by making the projection 26 of its block 2, abut against one of the long sides of the recess 13. The side usually selected for this purpose has been the one next the wheel axis. This practice has necessitated accurate machining and fitting to attain the desired result in the factory before a machine is sent to its user, and the alternate expansion and contraction of a mold block 2, wear of the wheel bush 12 against the top of the axle 4 and of that top, wear of the studs (not shown) projecting rearwardly from the vise frame 24 and with which corresponding holes 28 in the wheel 3 engage to steady the latter in its casting and ejecting positions, and wear of the said holes, all during the use of the machine by its user, soon spoil that result.

25. When the wheel 3 has a plurality of slots 1, the adjustment of them is a more serious matter still, because of the necessity of each slot of the plurality being at the correct radial distance from the axis of the wheel, in order that all the lines, irrespective of the particular slot in which they were cast, may receive the same treatment from the knives 5, 6.

The only way in which the said result could be re-attained, has been (and is) to ignore both the projection 26 and cavity 13, and to rely upon the screws 11, their round holes and the fit of the flange 15 to the face of the wheel 3. The objection to this reliance is that the slot 1 is not held by the method relied on, in its correct right angled position with reference to the wheel face.

Hence arises the necessity of a datum line independent of each of the surfaces just enumerated, and the one devised by the present invention is a constant one, parallel with a correct position of a slot 1. When the mold carrier is a wheel such as the one shown that line is a diameter of that wheel 50 and its axle 4, because it passes through the axis of the latter, and the position of that axis is constant in both a vertical and a lateral sense. Each slot 1 has its own datum line. The invention therefore consists in means by which a slot 1 and the ascender knife 5 can be adjusted independently of each other respectively to and from and with reference to the datum line for that slot.

The means for so adjusting a slot 1 are 60 as follows: The radial dimension of the cavity 13—Fig. 2—is increased and the screw holes 14 in the flange 15 on the body portion 9 of a mold block 2 may be slotted in the direction of adjustment, or, as shown 65 in Fig. 1, drilled larger than the screws,

to allow of the adjusting movements of the said block in either direction. The adjusting means consist of a set screw working in the said flange 15, near each end of it, at right angles with its length, and having its head 17 toward the datum line. Each screw 16 passes through a stout cross head 18, fast to and projecting to the front of the wheel 3. Both cross heads 18 of any mold block 2 must be operatively on a line parallel with a diameter of the wheel 3, and when there is a plurality of mold blocks the respective lines must be at the same distance from the datum line. Neither screws of a mold block may have axial motion. To prevent this, there is, preferably, a collar 19 fast on a screw shank on each side of a cross head 18, thus keeping the shoulder of a screw within the cross head. There may also be a locking nut 20 on each shank to engage with the flange 15 after adjustment. Both screws 16, 16, are of the same pitch, and there is, preferably, a scale and index associated with each, say index on the cross head 18 and scale on one of the collars 19, 90 to indicate the adjustment distance equal to one or an aliquot part of one turn of a screw 16. Thus, the mold block may be regarded in a sense as a floating one. It is adjusted by slackening the locking nuts 20 (if necessary) and the fixing screws 11, turning both set screws 16 in succession or together for the same distance in the required direction, and tightening up the locking nuts and the fixing screws. All the molds on the wheel are so adjusted before starting the machine and from the datum line.

Thus the expensive machining and fitting above mentioned, are obviated, and an easy and, at the same time, accurate adjustment 101 of each mold block effected.

A like combination of cross heads 21, set screws 22, collars 23, scale and index, is applied to the ascender knife 5, the cross heads 21 being, of course, fast, not on the wheel, but on a suitable part of the machine, such part being on the Mergenthaler machine above mentioned, its vise frame 24.

Thus each mold block 2 and the ascender knife 5 are adjustable easily, accurately, independently of each other and in respect of a common datum line. This independence may frequently be advantageous, because it does not follow that because a plurality of molds and a knife must be adjusted by a common datum line, that each will require the same linear amount of adjustment.

Having described our invention, we declare that what we claim and desire to secure by Letters Patent is:—

1. In a typographical casting machine, the combination of a slotted mold, a carrier whereon the mold is mounted, and adjustable supporting means for tilting the mold relatively to the carrier to secure the

parallelism of its slot with a constant datum line.

2. In a typographical casting machine, the combination of a slotted mold, a rotary wheel formed with an enlarged recess wherein in the mold is mounted, and two independent adjusting devices supporting the mold free of the lower wall of said recess and adapted by their adjustment to tilt the mold 10 relatively to the carrying wheel to secure the parallelism of its slot with a constant datum line.

3. In a typographical casting machine, the combination of a slotted mold, a rotary wheel formed with an enlarged recess wherein in the mold is mounted, a pair of set screws arranged at the opposite ends of the mold and supporting it free of the lower wall of the recess and adjustable independently to 20 tilt the mold at its opposite ends relatively to the carrying wheel to insure the parallelism of its slot with a constant datum line, and clamping screws passing through en-

larged openings in the mold for holding it in its adjusted position.

4. In a typographical casting machine, the combination of a pair of parallel straight-edged trimming knives, a slotted mold wherein the slug is cast, a carrier whereon the mold is mounted and adapted to present it periodically in operative relation to the trimming knives, and means attached to the carrier for giving support to the mold thereon and adjustable at will to tilt the mold relatively to the carrier to 35 insure the parallelism of its slot with the cutting edges of the trimming knives when presented thereto.

In witness whereof we have hereunto set our hands in the presence of two witnesses. 40
